UNITED STATES PATENT OFFICE.

CARL MAISEL, OF NEW YORK, N. Y.

FLUID-DISCHARGING DEVICE.

1,358,089.

Specification of Letters Patent. Patented Nov. 9, 1920.

Application filed January 17, 1920. Serial No. 352,114.

To all whom it may concern:

Be it known that I, CARL MAISEL, a citizen of the United States, and a resident of the city of New York and State of New York, 5 have invented a new and useful Fluid-Discharging Device, of which the following is a specification.

This invention relates to fluid discharging devices and has for its primary object to 10 provide a device which may be readily applied to containers for gasolene, petroleum, or other combustible fluids or gases, whereby the fluid may be freely decanted and air automatically supplied to the container so as 15 to thereby prevent suction at the discharge end of the emission tube and thus obviate the possibility of an explosion which might otherwise occur when the combustible fluid is poured upon or in proximity to a fire or 20 flame.

More particularly my present improvement consists in the provision of a device for the above purpose which in its preferred form embodies a stopper or closure for the 25 opening in the container head, an emission tube extending axially through the closure and having an inlet for the fluid, and a capillary tube extending through the closure along the side of the emission tube and having 30 its discharge end disposed below the fluid inlet of the emission tube.

With the above and other objects in view, the invention consists in the improved fluid discharging device as above described, and in 35 the form, construction, and relative arrangement of its several parts as will be herein-after more fully set forth, illustrated in the accompanying drawing and subsequently incorporated in the subjoined claim.

40 In the drawing wherein I have illustrated one practical embodiment of the device and in which similar reference characters designate corresponding parts throughout the several views, Figure 1 is a longitudinal sectional view showing my improved fluid discharging device applied to the outlet neck of a container.

Fig. 2 is a side elevation of the device detached from the container.

50 Fig. 3 is a detail section taken on the line 3-3 of Fig. 1.

Referring in detail to the drawing, 5 designates the body of a container and 6 the discharge or outlet neck thereof. While for 55 convenience, I have shown my device applied to this form of container which is in

general use, it will also be apparent as the description proceeds that the adaptation and use of the device is not to be so limited, as it may, with resort to obvious mechanical 60 changes, be rendered adaptable to containers of various other constructions.

As herein shown, the device consists of a plug or stopper 7 which is of conical or tapering form and is preferably formed of 65 rubber, cork, or other like material offering high frictional resistance when tightly engaged with the edge of the opening in the outlet neck of the container. This stopper is suitably fixed to a frusto-conical body 70 member 8 which projects beyond the larger end of the stopper 7 and in the opposite sides of which the resiliently yieldable rods 9 are securely fixed at one of their ends. These rods at their other ends are adapted 75 for contact with the opposite sides of the outlet neck 6 of the container and constitute additional means for securely holding the stopper 7 in place. The lower end of the body member 8 is formed with an annular 80 flange or bead 10 to prevent longitudinal movement of the plug or closure 7 thereon.

An emission tube 11 extends axially through the body member 8 and at its upper end is laterally curved as at 12. A closure 85 cap 13 for this discharge end of the emission tube is attached to the tube by a chain 14 or other suitable flexible connection. Below the body member 8 the emission tube 11 is provided with a plurality of circularly arranged series of fluid inlet openings 15. The lower end of said tube is closed and adjacent thereto is provided with a drainage opening 16 whereby the fluid remaining in that portion of the tube below the openings 15 may 95 readily drain back into the container.

A capillary tube 17 also extends through the body member 8 alongside of the emission tube 11. This tube 17 is laterally projected at its upper inlet end as indicated at 18, 100 while its lower end, which preferably extends below the lower end of the emission tube 11 is laterally curved as at 19.

In the use of the device as above described, when it is desired to decant the fluid from 105 the container, the latter is tilted in the usual manner, so that the fluid will pass through the openings 15 into the emission tube 11 and be discharged through the outlet end 12 thereof. As the fluid flows through the outlet openings 15, atmospheric air in approximately the same volume as the outlet flow 110

of the fluid is drawn through the tube 17 and discharged into the container below the point of fluid outlet. Thus the space formerly occupied by the fluid is replaced with air and 5 the creation of suction at the discharge end 12 of the emission tube is thereby obviated. Accordingly there will be a free and uninterrupted flow of the fluid through the emission tube, and when the device is used for 10 pouring petroleum, or other combustible fluid upon a fire, all danger of explosion is eliminated, since the flames will not be drawn into the tube 11.

From the foregoing description, consider 15 ed in connection with the accompanying drawing, the construction, manner of operation, and several advantages of the invention will be readily understood. The device is of very simple construction, can be easily 20 and quickly applied to the container in its operative position, and is efficient and reliable for the purpose in view. Of course, the plug or closure of friction material and the resilient rods 9 might be replaced with an 25 ordinary screw cap for engagement upon the threaded neck of a container. Likewise, the openings 15 through which the fluid enters the emission tube might be otherwise arranged than as indicated in the drawing, 30 while this emission tube, as well as the air

inlet tube 17, can be secured in the closure plug or cap in various ways. It is accordingly to be understood that while I have herein shown and described one practical embodiment of the invention, the device is 35 nevertheless susceptible of many modifications, and I therefore reserve the privilege of adopting all such changes as may be fairly embodied within the spirit and scope of the invention as claimed. 40

I claim:

In a fluid discharging device, a closure plug for a container, an emission tube extending axially through the closure plug and adapted to project into the container, the latter end of the tube being closed and said tube having a plurality of fluid inlet openings in spaced relation to said closed end thereof, said tube having an additional drainage opening adjacent to its closed end and below the 50 series of fluid inlet openings, and a capillary tube extending through the closure plug alongside of the emission tube and projecting beyond the closed end of the emission tube to deliver air into the container in approximately the same volume as the outflow of the fluid. 55

In testimony that I claim the foregoing as my invention, I have signed my name.

CARL MAISEL.
